UNITED STATES PATENT OFFICE.

LOUIS R. HAMLIN AND JESSE JACKSON, OF KOKOMO, INDIANA, ASSIGNORS TO THE GLOBE STOVE & RANGE CO., OF KOKOMO, INDIANA.

ELECTRIC SADIRON.

Application filed July 13, 1921. Serial No. 484,378.

To all whom it may concern:

Be it known that we, LOUIS R. HAMLIN and JESSE JACKSON, citizens of the United States, residing at Kokomo, county of 5 Howard, State of Indiana, have invented certain new and useful Improvements in Electric Sadirons, of which the following is a specification.

This invention relates to improvements in 10 electric sad irons.

The main objects of this invention are:

First, to provide in an electric sad iron an improved terminal clip for the resistance element.

15 Second, to provide in an electric sad iron an improved means for mounting and insulating the terminal posts.

Third, to provide an improved electric sad iron in which the parts are simple and 20 economical in structure and very easily assembled.

Further objects, and objects relating to structural details, will definitely appear from the detailed description to follow.

25 We accomplish the objects of our invention by the devices and means described in the following specification. The invention is clearly defined and pointed out in the claims.

30 A structure which is a preferred embodiment of our invention is clearly illustrated in the accompanying drawing, forming a part of this application, in which:

Fig. I is a plan view of the body portion 35 of an electric sad iron embodying the features of our invention, the shell and handle being omitted as are also the attaching means for the shell.

Fig. II is a rear elevation of the parts 40 shown in Fig. I.

Fig. III is a detail vertical section on a line corresponding to line 3—3 of Figs. I and II.

Fig. IV is a detail section through one 45 of the terminal clips, showing means for securing the terminal clip to the resistance element.

Fig. V is a plan view of the blank for one of the terminal clips.

50 Fig. VI is a rear view of the terminal post supporting and insulating plate,

shown in separated relation to show structural details thereof.

In the drawings similar reference characters refer to similar parts throughout the 55 several views.

Referring to the drawing, we provide a pair of body members 1 and 2, the body member 2 being superimposed upon the body member 1, the latter being the shoe of 60 the iron.

The heating element is shown conventionally at 4 and includes a resistance wire or element 5. The arrangement of this wire in the heating element is not shown as these 65 details are unimportant so far as our present invention is concerned.

The upper body member 2 is provided with a recess 6 at its rear end adapted to receive the insulating plates 7 and 8. These 70 plates are arranged in a superimposed relation as shown in Fig. II. The lower plate 7 is provided with a hole 9, while the upper plate 8 has a slot 10 registering with the hole 9. 75

The screw bolt 11 is threaded into the bottom plate 1 and is provided with a clamping nut 12 for the upper body member, the upper body member having a recess 13 for this nut. The bolt 11 extends through the 80 hole 9 and the slot 10 to receive the clamping nut 14 by means of which the insulating plates are clamped together and secured in position.

The lower insulating plate 7 is provided 85 with downwardly projecting lugs 15 overlapping the rear end of the upper body member 2 and with inclined grooves 16 aligned with these lugs. The upper plate is provided with lugs 17 fitting into the 90 grooves 16 of the lower plate and with an inclined boss 18 supporting the terminal posts 19.

The resistance wires are connected to these 95 terminal posts by means of the clips 20 which are folded over the lugs 15 and their upper ends disposed in the grooves 16, the posts being secured to the clips at 21. The resistance wires are secured to the plates by means of the clamping tongues 22 which 100 are folded upon the ends of the resistance wires and secured by spot-welding at 23.

These clips are preferably provided with holes 24 into which the ends of the wires project, as shown in Fig. IV. These terminal clips are preferably formed of Monel 5 metal, which is well adapted for the purpose, being a good conductor, and, by securing the tongue by welding as described, a very effective connection for the resistance wire is obtained; also one which does not 10 injure the resistance wire or cause it to break as the parts are manipulated in assembling.

By slotting the upper insulating plate the 15 posts may be inserted and clamped to the upper plate and the upper plate then slipped into position on the lower and secured by tightening the nut 14.

The several parts of our improved sad iron are simple and economical to produce 20 and are very easily assembled.

Having thus described our invention, what we claim as new and desire to secure by Letters Patent, is:

1. In an electric iron, the combination of 25 a body comprising a pair of superimposed members, the upper of which is recessed at its rear end, a heating element interposed between said body members and comprising a resistance wire, resistance wire 30 terminal clips having bendable portions, terminal posts to which the bendable portions of said terminal clips are secured, superimposed insulating plates disposed in said body member recess, the lower plate 35 having a hole therein and the upper a slot registering with the hole, the lower plate having downwardly projecting lugs at its rear end overlapping the rear end of the upper body member and inclined grooves 40 aligned with its said lugs, the upper plate being provided with lugs projecting into said grooves and with an inclined boss through which said terminal posts are disposed, said terminal clips being folded over 45 the lugs on the lower plate and extended into the grooves thereof, and a clamping bolt connecting said body members and projecting through said registering hole and slot in said insulating plates and provided with 50 a clamping nut engaging the top plate.

2. In an electric iron, the combination of 55 a body comprising a pair of superimposed members, the upper of which is recessed at its rear end, a heating element interposed between said body members and comprising a resistance wire, resistance wire terminal clips having bendable portions, terminal posts to which the bendable portions of said 60 terminal clips are secured, superimposed insulating plates disposed in said body member recess, the lower plate having downwardly projecting lugs at its rear end overlapping the rear end of the upper body member and inclined grooves aligned with 65

its said lugs, the upper plate being provided with lugs projecting into said grooves and with an inclined boss through which said terminal posts are disposed, said terminal clips being folded over the lugs 70 on the lower plate and extended into the grooves thereof, and means for securing said insulating plates.

3. In an electric sad iron, the combination of 75 a body comprising a pair of superimposed members, the upper of which is recessed at its rear end, a heating element interposed between said body members and comprising a resistance wire, resistance wire terminal clips having bendable portions, 80 terminal posts to which the bendable portions of said terminal clips are secured, superimposed insulating plates disposed in said body member recess, the lower plate having a hole therein and the upper a slot 85 registering with the hole, the lower plate having portions at its rear end overlapping the rear end of the upper body member, said terminal post being mounted on the upper plate to project therethrough, said terminal 90 clips being folded over the rear edge of said lower plate, and a clamping bolt connecting said body members and projecting through said registering hole and slot in said insulating plates and provided with 95 a clamping nut engaging the top plate.

4. In an electric iron, the combination of 100 a body comprising a pair of superimposed members, the upper of which is recessed at its rear end, a heating element interposed between said body members and comprising a resistance wire, resistance wire terminal clips having bendable portions, terminal 105 posts to which the bendable portions of said terminal clips are secured, superimposed insulating plates disposed in said body member recess, the lower plate having portions at its rear end overlapping the rear end of the upper body member, said terminal post being mounted on the upper plate to 110 project therethrough, said terminal clips being folded over the rear edge of the lower plate, and means for securing said insulating plates.

5. In an electric iron, the combination of 115 a body, a heating element therefor comprising a resistance wire, a terminal clip for said resistance wire formed of sheet metal and having a hole therein through which the end of the resistance wire is disposed, an integral tongue folded upon the resistance wire and secured to the clip by welding whereby the end of the resistance wire is secured to the clip, a terminal post secured to said clip, and an insulating plate 120 on which said post is mounted.

6. In an electric iron, the combination of 125 a body, a heating element therefor comprising a resistance wire, a terminal clip for said resistance wire formed of sheet metal 130

and having a hole therein through which our hands and seals in the presence of two
the end of the resistance wire is disposed,
an integral tongue folded upon the resist-
ance wire and secured to the clip by weld-
5 ing whereby the end of the resistance wire
is secured to the clip, and a terminal post
secured to said clip.
In witness whereof, we have hereunto set
